UNITED STATES PATENT OFFICE.

GEORGE H. WHITTINGHAM, OF BALTIMORE, MARYLAND.

TERMINAL FOR RHEOSTATS.

Application filed June 18, 1925. Serial No. 38,009.

In my prior applications, Serial Number 725,555, filed July 12, 1924, and Serial Number 17,628, filed March 23, 1925, I have shown in detail a rheostat in which the resistance elements consist of flat metal ribbons wound on edge and supported on flat supporting members which extend between cross bars in a rheostat frame, and also flat clamping members adapted to engage the coils, these members constituting terminals for the coils and connections between the coils. Where the rheostats are to be used in situations where they are not subject to vibration, the conductors from the controllers may be connected directly to the flat terminals mentioned with satisfactory results, but where the rheostats are used for street car work, for instance, where the rheostats are subject to much vibration, it is desirable to have a terminal anchored to the frame of the rheostat for holding the heavy wires and cables leading to and from the controller.

The purpose of the present invention is to provide a terminal which can be readily applied to the frame of such a rheostat and which will be anchored so that it cannot be affected by vibration, and which can be readily connected to the flat terminals or connectors before mentioned, which are secured to the resistance elements.

In the accompanying drawing,

Fig. 1 is a top plan view of a rheostat having four resistance elements;

Fig. 2 is an end view of the same, looking from left to right in Fig. 1;

Fig. 3 is a section on the line 3—3 of Fig. 1, showing the anchored terminal in central section;

Fig. 4 is a side view of the terminal shown in Fig. 3;

Fig. 5 is a side view of a terminal composed of two parts;

Fig. 6 is an edge view of the terminal shown in Fig. 5; and,

Fig. 7 is a side view of the rheostat frame on a small scale.

Referring to the drawing, *a* indicates the frame of a rheostat comprising side bars 1—1, connected at their ends by bolts 2, and similar side bars 3—3, connected at their ends by bolts 4. The side bars 1 are connected to the side bars 3 by vertical bars 5, through which the bolts extend. These bars, as shown, are all composed of flat metal strips, and the bars and bolts constitute a light open frame. The bolts 4, which constitute

cross bars at the ends of the frame, are covered by tubes of insulating material 6. Flat metal strips 7, covered by insulating material, support the coils 8, 9, 10, and 11, 60 which are threaded on to the insulators. The coils, of course, may be connected in any suitable way. In the drawing, the coil 8 has a flat terminal 12 clamped to one end, and the opposite end of this coil is connected to 65 the coil 9 by similar connectors 13 and 14 and a flexible conductor 15. The left hand ends of the lower coils 9 and 10 are connected together by a flat connector 16, and the right hand end of the lower coil 10 is 70 connected to the corresponding end of the coil 11 by connectors 17 and 18 and flexible conductor 19, and the left hand end of the upper coil 11 is provided with a flat terminal 20. Thus, as shown in the drawing, 75 the coils are connected in series, with the terminals 12 and 20, adjacent the upper cross bar 2.

Upon the cross bars 2 and 4 are shown three anchored terminals *t*, *t'* and *t''*. Each 80 terminal, as shown in Figs. 3 and 4, comprises a flat metal strip longer than the distance between the bars at one end of the frame and provided near its ends with spaced openings 21 and 22, adapted to fit 85 over the bars 2 and 4 and the insulating tubing thereon. Each terminal has suitable clamping means 23, at a point between the openings 21 and 22, and it also has at one end a head 24 provided with openings 25 90 and 26, adapted to receive the ends of cables or conductors which may be secured within the openings by set screws 27.

The several supporting bars for the resistance units and the several anchored terminals are insulated from the bar and from one another and spaced apart by suitable tubular spacing devices 28, which may be forced toward one another by tightening the 95 nuts shown on the ends of the cross bars. The anchored terminals may be placed at 100 one or both ends of the frame, as desired. In the drawing, three are shown at one end of the frame. It will be seen that when the nuts on the cross bars are tightened, the terminals *t*, *t'* and *t''* will be firmly secured to a pair of cross bars and therefore they cannot swing about either of the bars or be laterally displaced by tugging of the cables which 105 connect them to the controller of a trolley car, for instance. The anchored terminals *t* and *t''*, as shown in the drawing, are con-

nected to the flat end terminals 12 and 20 on the coils 8 and 11 by flexible conductors 29 and 30, respectively, which conductors are secured to the anchored terminals by the 5 clamping devices 23. As the anchored terminals are in fixed relation to the terminals on the coils, there is no stress applied to the latter. The central anchored terminal t' is shown connected by a flexible conductor 31 10 to the connector 16, which engages the left hand ends of the lower coils 9 and 10.

The anchored terminals are provided with two openings in their heads so that leads from a controller may be connected to the 15 heads and different rheostat units may be connected together by inserting the leads and the connecting wires in the different openings and clamping them to the heads.

The anchored terminals may be of metal 20 cast in one piece, as shown in Figs. 3 and 4, or they may be composed of metal stampings as shown in Figs. 5 and 6. In these latter 25 views, each terminal t' is composed of two flat strips of sheet metal 32, of like form, connected together by the central clamping device 23^a, and also by bolts 33, passing through the head of the terminal. The head is suitably shaped to form the openings 34 and 35, between the parts, for receiving 30 cables or conductors.

What I claim is:

1. In a rheostat, a frame having cross-

bars at each end, coil supporting members supported at their ends by said bars, edge wound resistance coils on said members, flat 35 clamps fitting on to said coils, a terminal rigidly secured to and insulated from two of said bars at one end of the frame, and a metal connection between said terminal and one of said clamps. 40

2. In a rheostat, a frame having cross-bars at each end, coil supporting members supported at their ends by said bars, edge wound resistance coils on said members, flat 45 clamps fitting on to said coils, a terminal rigidly secured to and insulated from two of said bars at one end of the frame, and a flexible metal connection between said terminal and one of said clamps.

3. In a rheostat, a frame having a pair of 50 parallel cross-bars at each end, coil-supporting members extending between and supported by the bars at opposite ends of the frame, a terminal having spaced openings 55 fitting over two of said bars at one end of the frame, said members and said terminal being insulated from the bars and from one another, and tubular spacing devices on the bars for spacing the several members and the terminal apart. 60

In testimony whereof I hereunto affix my signature.

GEORGE H. WHITTINGHAM.
